UNITED STATES PATENT OFFICE.

WILLIAM BLACKMORE, OF SHARON, PENNSYLVANIA, ASSIGNOR TO NATIONAL MALLEABLE AND STEEL CASTINGS COMPANY, OF CLEVELAND, OHIO, A CORPORATION OF OHIO.

SHOCK-ABSORBING MECHANISM.

Application filed December 22, 1926. Serial No. 156,315.

Fig. 1 is a horizontal section of a shock absorbing mechanism embodying my invention; Fig. 2 is an end of elevation thereof with the wedge follower removed; Fig. 3 is an elevation of the inner face of the wedge follower; Fig. 4 is a side elevation, partly in section, of the wedge follower; Fig. 5 is a side elevation of one of the shoes; Fig. 6 is a rear elevation thereof; Fig. 7 is a front elevation of the other of the shoes; and Fig. 8 is a side elevation thereof.

My invention relates to shock absorbing mechanism, and particularly to friction draft gears for railway vehicles of the type described in my co-pending application 79,602, filed January 6, 1926. My invention comprises a novel and effective means for releasing the parts after compression and various features which I shall hereinafter describe and claim.

Referring to the drawings, the central friction member 2 has longitudinally-extending, outwardly radiating arms 3 having diverging friction faces and terminates at its rear end in an enlarged base 4. Friction shoes 5 and 5^a seat upon the friction faces of the outwardly radiating arms 3. The friction shoe 5 has a wedging surface 6 engaged by a wedging surface 7 on the wedge follower 8. A rearwardly extending dowel 9 forms a spring seating surface, preferably engaged by the inner coil 10 of a spring element which at its rear end bears against the base 4. The outer coil 11 of the spring element likewise bears at its rear end upon the base 4, but at its forward end engages a surface 12 on the wedge follower 8. The rear face of the shoe 5 from which the dowel 9 projects may be offset sufficiently to keep the outer spring coil 11 normally out of engagement with the shoe. It will be seen that the surface 12 against which the outer spring coil 11 bears extends somewhat over half the circumference of the end of the spring. Also, if desired, the shoe 5 need not be offset to the extent shown, but may afford a bearing for the outer coil spring 11, in which event the spring pressure will be divided between the shoe 5 and the wedge follower 8.

The shoe 5^a on its outer surface has a ball-shaped projection 13 which engages a correspondingly shaped socket 14 in the wedge, thus forming a ball and socket engagement

with the shoe. Against the rear face of the shoe 5^a bear both the inner spring coil 10^a and the outer spring coil 11^a. The outer spring coil 11^a preferably bears both against the shoe 5^a and the surface 12^a on the follower wedge, while the inner coil 10^a bears entirely against the rear surface of the shoe 5^a.

As the gear is compressed and the follower 8 moves inwardly, a wedging action is set up between the follower and the shoe 5, forcing the shoe against the arms 3 of the central friction member 2. As the follower 8 is free to move laterally and is caused to so move by reason of its engagement with the inclined rear face 6 on the friction shoe, it will transmit the pressure caused by its wedging engagement upon the shoe 5 to the shoe 5^a through the ball and socket engagement, so that the shoe 5^a will be forced against the central member with a force equal to that on the shoe 5.

As the pressure abates, the follower wedge 8 will be forced off of the shoe 5 by the direct pressure of the outer coil 11, thus loosening the wedging grip of the wedge 8 upon the shoe 5, and after this grip has been broken, the coils 10^a and 11^a act to return opposite sides of the follower, and with it the shoe 5^a, back to normal position.

I have found that sticking is apt to occur when the releasing means is applied directly and uniformly to the follower or shoes. With my improved mechanism, however, the force of the spring 11 exerted on the surface 12 of the follower actually tips the follower and this breaks the adhesion of the shoes 5 and 5^a and the follower and consequently leaves them and both sides of the follower to be pushed outwardly by the springs 10, 10^a, 11 and 11^a. It will thus be seen that there is a relative sliding movement in release between the one side of the follower 8 and the shoe 5, and that this gives a rotative movement of the follower about the ball and socket joint in the other side of the device, which is brought about through an extended leverage effected by the spring 11 against the part 12 of the wedge.

Another advantage of my improved draft gear is that it may be applied to cars employing the U. S. R. A. type of yoke in which, as is shown in Fig. 1, the shoes 5

and 5^a will be in the same horizontal plane. Normally, when so applied its weight causes the free end of the central member to work gradually down until it is in contact with the lower face 15 of the follower wedge, with the result that the wedge pads 7 will then seat a little offcenter on the shoes. With my improvement, however, the shoe 5^a can have no movement relative to the follower other than a rotary one by reason of its ball and socket joint. Hence, its only movement relative to the central member is a movement longitudinally of such member. It will therefore appear that the follower wedge can not shift bodily laterally relative to its bearing on the arms of the central member and can therefore not get out of line.

The terms and expressions which I have employed are used as terms of description and not of limitation, and I have no intention, in the use of such terms and expressions, of excluding any mechanical equivalents of the features shown and described, or portions thereof, but recognize that various structural modifications are possible within the scope of the invention claimed.

What I claim is:

1. In a frictional shock absorbing mechanism, a longitudinally-extending included friction member having arms with longitudinally-extending friction faces; friction shoes seating on said faces; a follower having a wedging engagement with one of said shoes and a rotative engagement with the other, and a plurality of springs operative in compression and release.

2. In a frictional shock absorbing mechanism, a longitudinally-extending included friction member having arms with longitudinally-extending friction faces; friction shoes seating on said faces; a follower having a variable engagement with each of said shoes but a wedging engagement with only one; and a plurality of springs operative in compression and release.

3. In a frictional shock absorbing mechanism, a longitudinally-extending included friction member having arms with longitudinally-extending friction faces; friction shoes seating on said faces; a follower having a ball and socket engagement with one of said shoes and adapted to exert wedging pressures on each of the said shoes, and a plurality of springs operative in compression and release.

4. In a frictional shock absorbing mechanism, a longitudinally-extending included friction member having arms with longitudinally-extending friction faces; friction shoes seating on said faces; a follower having a wedging engagement with one of said shoes and a rotative engagement with the

other, and a plurality of spring elements one of which acts to tilt the follower and thereby break the adhesion between wedge and shoe 65 by an offcentered application of force.

5. In a frictional shock absorbing mechanism, a longitudinally-extending included friction member having arms with longitudinally-extending friction faces; friction 70 shoes seating on said faces; a follower having a wedging engagement with one of said shoes and a rotative engagement with the other, and a plurality of spring elements arranged symmetrically on either side of 75 said member, one of which has a bearing upon the follower at the side opposite the said rotative bearing and in release causes it to rotate about the said bearing.

6. In frictional shock absorbing mechanism, a longitudinally-extending included friction member having longitudinally-extending friction faces; friction shoes bearing on such faces; a follower engaging said shoes adapted to wedge them against said faces; and a plurality of spring elements, one of which bears against a shoe and the follower, and another against follower alone, whereby a tilting pressure is exerted against 90 one side of the follower in release.

7. In frictional shock absorbing mechanism, a longitudinally-extending included friction member having a plurality of longitudinally-extending friction faces; a friction shoe engaging each of such faces, one of said shoes having an inclined wedging face; a follower engaging the wedging face of the said shoe; a compression spring element arranged to resist the inward movement of a shoe and follower relative to the central friction member; another shoe having a rotative engagement with said follower; and a second compression spring element, the first mentioned spring element in release being effective to cause rotation of the follower to release it from its wedging engagement with the shoe first mentioned and break the adhesion of the said wedge and shoes.

8. In frictional shock absorbing mechanism, a longitudinally-extending friction member, friction shoes in frictional contact with said friction member, a wedge member engaging said shoes and adapted to move them longitudinally of said friction member, said wedge having a wedging engagement with one of said shoes and a rotative engagement with another of said shoes whereby the wedge is substantially incapable of longitudinal movement relative to one of said shoes, and a plurality of springs operative in compression and release.

WILLIAM BLACKMORE.
